UNITED STATES PATENT OFFICE.

NICHOLAS KOPP, OF PITTSBURGH, PENNSYLVANIA.

DESIGN FOR A SHADE.

54,103.

Specification for Design.

Patented Nov. 4, 1919.

Application filed June 11, 1919. Serial No. 303,487. Term of patent 7 years.

To all whom it may concern:

Be it known that I, NICHOLAS KOPP, a citizen of the United States, residing at Pittsburgh, in the county of Allegheny and State of Pennsylvania, have invented a new, original, and ornamental Design for a Shade, of which the following is a specification, reference being had to the accompanying drawing, forming part thereof.

The figure is a perspective view of a shade illustrating my new design.

I claim:—

The ornamental design for a shade, as shown.

NICHOLAS KOPP.

Witnesses:

J. M. GEOGHEGAN,
LOIS WINEMAN.
